UNITED STATES PATENT OFFICE.

EDWARD HENRY MOYLE, OF LOS ANGELES, CALIFORNIA.

ADJUSTING AND SAFETY MEANS FOR CRUSHER-JAWS.

1,281,055.

Specification of Letters Patent.

Patented Oct. 8, 1918.

Application filed February 12, 1915. Serial No. 7,720.

To all whom it may concern:

Be it known that I, EDWARD HENRY MOYLE, a citizen of the United States, residing at Los Angeles, in the county of Los Angeles and State of California, have invented a certain new and useful Adjusting and Safety Means for Crusher-Jaws, of which the following is a specification.

In a companion application I have shown, 10 described and claimed a rock crusher, patented June 8th, 1915, No. 1,142,116. And in this application I do not wish to make such claims herein.

My invention relates to a crusher and 15 pulverizer for rock and ores.

Objects of this invention are to provide a device for effectively reducing the rock or ore to a condition desired by successive stages, consisting in first breaking the rock 20 or ore along the lines of least cleavage, then crushing the same and finally transforming the same into a pulverulent mass of a desired mesh; to provide a simple device made of the fewest parts, readily dissociable; having a minimum of bearings convenient for 25 transportation into difficultly accessible places, and quickly assembled; to provide a crusher in which the degree of fineness of the ore or rock may be regulated during 30 the operation of the same; to provide a device in which no material damage will be occasioned by the entry of any substance harder than that calculated for the crushing 35 power of the jaws; and finally to provide an adjustment for the jaw of the crusher which will be mechanical and simultaneous and said adjustment in actuation with the thrust bar.

With these and other objects in view, this 40 invention consists of the features, and details of construction, separately and in combination, described in connection with the accompanying drawings, and then more particularly pointed out in the claims.

45 In the drawings,

Figure 1 is a plan view of my rock crusher.

Fig. 2 is a side elevation of the crusher, 50 one of the side plates being removed to disclose parts otherwise hidden.

Fig. 3 is an end view showing the means for adjusting the thrust bar as seen looking in the direction of the arrows 3 in Figs. 1 and 2.

Fig. 4 is a fragmentary vertical sectional detail taken from the line 4-4 of Fig. 3.

In all, or nearly all, types of rock crushers, the base is a solid heavy casting, with many bearings, requiring expensive and careful machining, and with a multiplicity of unequal strains, the weakest of which is not perceptible until actual disruption occurs. Generally the base in the ordinary class of crushers, consists of a massive sole plate, with weighty integral side and rear walls, which with the other necessary adjuncts of the machine, makes a cumbersome product, difficult to transport, and more difficult if not impossible, to repair when fractured or broken. In elimination of 70 these disadvantages, the present invention consists of two side plates 1 and 2, having suitable flanges 3 and 4, on the bottom, provided with bolt holes 5 and 6, for fastening the same to a suitable supporting structure. These plates are tied together at one end by a shaft 7, and rod 8, carrying a spacer tube or pipe 9, and at the other end by a trunnion 10, the shaft 7, and trunnion 10, serving additional purposes to appear 75 hereinafter. Between and fulcrumed in said plates by fulcrum pin or shaft 11, which also serves to tie said plates, is a lever or actuating crushing jaw 12, of cross-sectionally U-shaped structure at one end, embracing and 80 connected by a pin 13, with a strut 14, to which reciprocatory motion is imparted through the medium of an eccentric 15, turned or fastened on said shaft 7, which carries on the outside of said plates, the 85 usual fly wheels 16, and loose and fixed pulleys 17 and 18, respectively. The lever 12, has a double bearing on the strut 14, whereby the friction is reduced to a minimum and the wearing life increased, the pin 13, serving principally to connect the lever with the strut.

On said lever or actuating crushing jaw 12, is removably fastened a crushing shoe 19, by counter sunk head bolts 19', the plane 100 of said shoe is ribbed or corrugated for a portion of its length, as shown at dotted line 20, and terminates in a curve 21, at a point below said ribs or corrugations. The aforesigned trunnion 10, forms a pivotal 105 support or bearing for a jaw 22, to which is arranged to be removably attached by countersunk bolts 23', a die plate 23, hav-

ing a plane, ribbed or corrugated, as at 24, and terminating in a substantially compound or ogee curve 25, coöperating with said curve 21, of said shoe 19, to levigate the 5 rock or ore. The jaw 22 is hung or supported off the center of gravity of the trunnion pin 10, in that position nearest to the lever or actuating crushing jaw 12, so that when the screws 35 and 36 are drawn out- 10 wardly or away from the thrust bar 29 and the jaw 12, the bottom part of jaw will automatically back or retract relatively to the laws of gravity, and in the direction of the screws 35 and 36. The disposition of said 15 shoe 19, and die plate 23, is in substantially the form of a Y, the crushing of the rock, fed from a hopper 26, immediately above said shoe and die plate, proceeding regularly and uniformly until the point between the 20 oppositely disposed and interacting curves 21 and 25, is reached, where the final trituration takes place and the finished product discharges below said shoe and die plate. By reason of the corrugated planes of the 25 shoe and die plate and the compound curves thereof, the rock or ore is crushed and powdered in successive steps to any desired mesh. In the wider portion of the crushing chamber formed by the shoe and die plate, 30 the crushing and breaking of the rock occurs by a reciprocatory motion of the lever, while the levigation of the rock occurs by a grinding motion of the curve of the shoe against the curve of the die plate, such motion being practically a circular one, since 35 the lower end of the curve 21, of the shoe is virtually concentric, or nearly so, with the arc described by the movement of the lever around the fulcrum point, while the rest of the curve is eccentric to such arc.

Between the face of the lever or actuating crushing jaw 12, and the shoe 19, and also between the face of the jaw 22, and the die plate 23, is preferably interposed a lead 40 filling or sheet, for the purpose of forming a perfect seat for the shoe and die plate, the rough and unplaned surfaces of which readily embed themselves into this plastic layer.

50 The die plate 23, normally rests on a shoulder 27, on the jaw 22, which as stated, is pivotally hung on the trunnion 10, and thus always connected in a pivotal manner with the side plates 1 and 2. The lower 55 portion of said jaw, at the rear and at approximately a point opposite the compound curve of the die plate 23, is furnished with an integral abutment 28, which bears against a thrust bar 29, transversely disposed in 60 elongated slots 30, and held in position by cotter pins 31, or in any other suitable manner. Adjustment of the thrust bar 29, to regulate the degree of fineness of the pulverized product, is effected, by adjusting 65 screws 35 and 36. The said thrust bar 29,

may be of cast iron or any other material calculated to resist the strain incident upon the crushing of rocks and ores of ordinary hardness, but incapable of withstanding any excessive pressure, such as would result 70 from the operation of the lever on metal substances or objects, as steel, iron, and the like, or in fact any hard substance not intended for treatment by this machine. Should any objects accidentally or otherwise, fall between the shoe and the die plate in the course of operation of the machine, the thrust bar will break, and permit the jaw to swing on its trunnion, thus insuring the other vital parts of the machine against 80 breakage. It will also be seen, that, as the adjustment for thrust bar, engages said bar through threaded orifices 35' and 36' in the rear of side plates 1 and 2 that said adjustment parts are also protected against break- 85 age or undue strain. The breaking of the thrust bar at the critical moment of excessive strain, is of the utmost importance, since by so doing, the balance of the machine is preserved intact. Being of inferior material 90 and intended for just such events, replacement of the same is coupled with no great expense, effort or labor. As is obvious, the adjustment of the thrust bar may be made during the operation of the crusher without 95 affecting or hindering the process of pulverization.

On the rear of said plates 1 and 2, is bolted or otherwise fastened, a plate 34, having orifices for the accommodation of screws 35 100 and 36, engaging threaded orifices 35' and 36' and extending inwardly from the rear of said plates into the slots 30, in which is disposed the thrust bar 29. On said screws 35 and 36, are keyed or fastened spur gears 105 37 and 38, between and in mesh with which, is an operating gear 39, journaled on an arbor 40, suitably supported in said plate 34. Said spur gear 39, is provided with a bevel gear 41, with which is in mesh a bevel gear 110 42, pinned or keyed on the end of a shaft 43, mounted in a suitable support 44, said shaft having a key wrench receiving end 45, by which the mechanism described, may be operated in either direction, as required. 115 The usual side liners 46, may be provided on the plates 1 and 2, suitable bolts serving to hold the same in position.

In making all necessary adjustments, it will be noted that the fulcrum of the lever 120 is not disturbed, but remains in its once fixed position. It will also be noted that on account of the few parts and the readiness with which the same are assembled and disassociated, the whole machine may be made 125 lighter and stronger than other machines now in use.

What I claim is,

1. A crushing mechanism comprising framing, an adjustable jaw mounted therein,

a thrust bar in guideways for adjustment, and extended transversely in the framing behind the said jaw for forming an abutment therefor, screws bearing against said thrust 5 bar for regulating the pressure upon the jaw, spur gears fastened to said screws, screws engaging with threaded orifices, an operating gear adapted to mesh with the said spur gears, and means for rotating said 10 gears fastened to said screws, when the thrust bar is to be adjusted.

2. A rock crusher mechanism having an adjustable crushing jaw, a breakable thrust bar extending transversely of the jaw 15 and behind the same, screws adapted to engage the end portions on said thrust bar, spur gears fastened on said screws for turning them, and operating gears intermeshing with said spur gears, a bevel gear integral 20 with said operating gear, a second bevel gear for actuating the first mentioned bevel gear, and a bracket carrying the same whereby the ends of the thrust bar may be simultaneously and equally moved.

3. In a rock crusher a frame, an adjustable jaw mounted between the sides of the frame, a breakable thrust bar passed through the frame and behind the jaw, screw means engaging the ends of the thrust bar, spur 25 gears fastened upon the screws so as to turn the same, and intermediate spur gears intermeshing with said screw spur gears for securing a simultaneous equal movement in said screws for advancing the thrust bar, the 30 jaw engaging the said thrust bar between the said screws, whereby the said bar may be sheared, or broken by excessive strain upon the said jaw.

4. A rock crushing mechanism comprising 40 side plates suitably spaced apart, an adjustable crushing jaw suspended between said side plates, the said side plates having openings formed therein, adjacent to the swinging end of said jaw, a thrust bar inserted 45 through said openings and behind the said jaw for forming an abutment for said jaw, feeding mechanism for setting up the said thrust bar to control the degree of fineness in the materials crushed, within the breaking 50 limit of said thrust bar, and a lever crushing member operating between the sides of the frame, opposite said jaw.

5. A rock crushing mechanism comprising 55 side plates forming a frame and having an adjustable crushing jaw pivoted transversely between them, a lever crushing mechanism also mounted between said plates, the said plates having apertures in their walls opposite the lower swinging end of the crushing 60 jaw, and a safety breakable thrust bar extending transversely through the side apertures in the side walls, and having its central portion arranged to bear strains upon

the crushing jaw, and means for adjusting the breakable bar in the side openings for 65 regulating the fineness of materials crushed.

6. In a rock crusher side plates, an adjustable jaw trunnioned at its upper end and interposed between said side plates, an adjustable thrust bar extending between and 70 through said side plates, adjustable means in the lower part of each side plate for moving the thrust bar sidewise toward said jaw to regulate the strain necessary to break the same, and mechanical lateral means for simultaneously operating said adjustable means for moving the bar to adjust said 75 jaw.

7. A rock crusher comprising side plates, an adjustable crushing jaw mounted between 80 them, a transverse thrust bar extending across the said jaw, forming a breakable abutment therefor under excessive strains, adjustable means mounted in said plates and engaging the bar out of alinement with the 85 said jaw, the said side plates inclosing the said screws sufficiently to protect them when the bar is broken, and intermeshing gearing for simultaneously adjusting the said screws whether the crusher is in operation or not. 90

8. A rock crusher comprising an adjustable crushing jaw and a co-operating movable jaw, side plates having the said jaws between them, abutment screws carried by the side plates, a thrust bar bearing at its 95 ends on said abutment screws and bridging the space between them, to support the said adjustable jaw, and intermeshing gearing for simultaneously adjusting the said screws to move the thrust bar toward the adjustable jaw. 100

9. In an ore crusher, a frame comprised of a plurality of side plates removably connected together, a lever or actuating crushing jaw, and an adjustable crushing jaw, 105 mounted between said plates, the side plates provided with apertures for inserting or removing a thrust bar, a thrust bar carried by said apertures in frame, a plate fastened to plurality of side plates and having means 110 for carrying an actuating adjusting mechanism comprising screws having spur gears fastened thereon, by which the said thrust bar can be projected or brought into engagement with the adjustable crushing jaw, 115 for setting the limit of the breaking strain, means for operating the spur gears and screws, and means for reciprocating the lever or actuating crushing jaw.

In testimony whereof I affix my signature 120 in the presence of two witnesses:

EDWARD HENRY MOYLE.
